UNITED STATES PATENT OFFICE.

MARTIN J. CARTER, OF ST. LOUIS, MISSOURI.

CAR-COUPLING.

SPECIFICATION forming part of Letters Patent No. 673,898, dated May 14, 1901.

Application filed February 17, 1900. Renewed October 15, 1900. Serial No. 33,104. (No model.)

To all whom it may concern:

Be it known that I, MARTIN J. CARTER, a citizen of the United States, residing at St. Louis, in the State of Missouri, have invented 5 certain new and useful Improvements in Car-Couplers; and I do hereby declare the following to be a full, clear, and exact description of the invention, such as will enable others skilled in the art to which it appertains to 10 make and use the same, reference being had to the accompanying drawings, which form part of this specification.

My invention relates to an automatic car-coupler which has for its object to simplify 15 and improve the construction of self-locking devices of this character and to render them more efficient in use by providing a car-coupler which is always sure of locking when the cars come together and which is not liable to 20 become inoperative under the most extreme circumstances; and my invention will be hereinafter fully described in the following specification and more particularly pointed out in claims.

25 Referring to the drawings, Figure 1 is a side elevation of the end portions of two cars coupled together with my improved locking device, one of said end portions being partly broken away and in vertical section. Fig. 2 30 is a side elevation of my coupling device detached, one of the heads being in vertical section. Fig. 3 is a horizontal sectional view through both heads of the coupler above the coupling-bars. Figs. 4 and 5 are detached 35 detail views of operating parts of the coupler.

Similar reference-numerals indicate corresponding parts in each figure of the drawings.

The cars are indicated by 1, each of which is provided with a coupling-head 2, which 40 may be connected to the car in any desired or approved manner. The coupler-heads are hollow and have flaring or bell-shaped mouths, as shown at their abutting ends. As each head is a substantial duplicate of the other, 45 a description of one will be sufficient. An extension or lug 3 is cast upon one side of the head, as indicated, and this lug is provided with a chamber or recess 8 to receive one end of the coupling-bar 5, which end is pivoted 50 within said chamber on a vertical pivot. The other or coupling end 6 of the bar 5 is designed to project into the interior of the op-

posed coupling-head and be locked therein, as will be more fully described hereinafter, and for the purpose of locking said end is bent 55 or curved upwardly to form a curved locking-face 23. It is desirable that the coupling-bars 5 have a limited lateral swinging movement on their pivots; but such movement must be confined to a certain space. Various 60 means may be employed to regulate and limit this movement—as, for instance, a spring 7 may be coiled around the pivot-pin of the coupling-bar, with one end connected to the wall of the chamber 8 and the other end to 65 the bar 5, as shown in the left coupling-head of Fig. 3, or, as is most preferable, in order to avoid the use of a spring in the coupler, as shown in the other coupling-head in said Fig. 3, the pivoted end of the coupling-bar 5 may 70 be V-shaped in plan view, as indicated at 9, and the sides 10 of the chamber, opposing the sides of the V-shaped end of the bar, may diverge from each other somewhat more than the sides of the end of the bar, and thereby 75 permit a limited lateral movement of the bar on its pivot, the bar being slightly held against the sides 10 of the chamber in its extreme movement.

There is a gravity locking-pawl 11 pivoted 80 within the coupling-head 2, which is of such length as to extend across the width of the chamber within the head and engage the vertical shoulders 12, which extend into the chamber from its opposite side. This pawl 85 11 is provided with an angular opening 13 within its upper rounded end to receive an angular bar 14, the latter being provided with cylindrical journals 15 and 18, which fit in suitable bearings in the coupling-head near its 90 upper side, the first-named journal 15 working in the bearing 16. (Shown in Figs. 1 and 2.)

By rocking the angular bar 14 in its bearings the locking-pawl 11 may be swung away from the shoulders 12 of the coupling-head, 95 and to effect this a crank-arm 17 is secured to one end of the angular bar 14, and this crank-arm is connected to a lever 22, pivoted in bearings 21 on the platform of the car by means of a link 20, so that the uncoupling of 100 the car may be easily effected by a slight movement of the lever 22 by a person standing on the platform of the car.

The lower end of the locking-pawl 11 is

curved, as indicated at 19, to correspond with the curvature 23 on the upper side of the coupling end of the bar 5. By this construction in coupling two cars together the end of the coupling-bar 5 being curved will push the pawl 11 within the coupling-head until the curved end of the bar 5 has entered sufficiently to permit the pawl to drop by gravity into the curve of the bar behind its front upturned end, when as the bar 5 recedes from the coupling-head the pawl 11 is drawn outward and tightly into the curve of the bar and against the shoulders 12 of the coupling-head, thereby automatically locking the cars together.

15 The coupling thus constructed has many advantages over devices heretofore used for this purpose, among which may be stated that as two coupling-bars are used in each set of couplings in the event one of such bars or any 20 part with which it coöperates becoming inoperative from any cause the other bar would be sufficiently strong to hold the cars together and prevent the train from breaking. The structure is also very simple, and consequently not liable to get out of order, and, further, it can be produced at a small cost compared with many of the more complicated structures for this purpose. As the gravity-pawl extends entirely across the open end of 25 the coupler it will entirely exclude snow, ice, and dirt and other foreign matter that frequently get into the opening of the coupling-head and obstruct its operation. Each coupling-bar being provided with so great a space 30 in which to swing in the head, no extra strain is brought to bear upon them in turning the shortest curve, as is the case in most other devices constructed for this purpose, and all danger of breakage at such times is therefore 35 avoided and at the same time the cars can be coupled or uncoupled while on a curve as easily as when in a straight line.

I am aware that car-couplers have been constructed with spring-catches, swinging hinges, 40 and inclined bolts, none of which are entirely safe, as the small hold which they have upon the end of the locking-bars renders them insecure, as they often break or slip over the small hold, causing the cars to separate, re-

sulting in great damage many times to person 50 and property, and such I do not claim; but

What I do claim as new, and desire to secure by Letters Patent, is—

1. A hollow coupling-head having a side extension, combined with a coupling-bar pivoted at one end to said extension, and its other end adapted to enter an opposing head, a spring in said extension to limit the lateral movement and center the said bar in the opposing coupling-head, and a gravity-pawl pivoted within the hollow head to engage and lock the end of the coupling-bar carried by the opposing head, as and for the purpose set forth. 55

2. In a car-coupling, the combination of opposing hollow coupling-heads, a coupling-bar pivoted to each head and adapted to extend into the opposing head, the free end of each bar having an upper curved locking-face, and a gravity-pawl pivoted within each head and 60 having a curved locking-face on its free end to coöperate with the locking-face on the bar of the opposing head, and shoulders to limit the outward movement of the pawl, as and for the purpose set forth. 70

3. In a car-coupling, the combination of opposing hollow coupling-heads, each head having a side extension, a coupling-bar pivoted at one end to each of said extensions and adapted to extend into the opposing head, 80 said bars having upper curved locking-faces on their free ends, means to limit the lateral movement and center the said bars, a gravity-pawl pivoted within each head and having a lower curved face on its free end to engage 85 the curved locking-face on the bar pivoted to the opposing head, shoulders extending into the chamber to limit the outward movement of the gravity-pawl, and means to swing it out of engagement with the coupling-bar, 90 as and for the purpose set forth.

In testimony whereof I have signed my name in presence of two witnesses.

MARTIN J. CARTER.
